(57) **CLAIM**

The ornamental design for a retractable hose reel, as shown and described.

DESCRIPTION

FIG. 1 illustrates a front perspective view of a retractable hose reel;

FIG. 2 illustrates a back perspective view thereof;

FIG. 3 illustrates a front elevational view thereof;

FIG. 4 illustrates a rear elevational view thereof;

FIG. 5 illustrates a left side elevational view thereof;

FIG. 6 illustrates a right side elevational view thereof;

FIG. 7 illustrates a top plan view thereof; and,

FIG. 8 illustrates a bottom plan view thereof.

The dashed broken lines depict portions of the retractable hose reel that form no part of the claim. The “RETRACTA” symbol is a registered trademark of Macnaught Pty Ltd (Registration Nos. 2797549, 5565245, 5659392, and 5659393) and forms no part of the claimed design.

1 Claim, 6 Drawing Sheets
